(57) **CLAIM**

The ornamental design for a combined phone stand and speaker, as shown and described.

DESCRIPTION

FIG. 1 is a front, right and top perspective view of a combined phone stand and speaker, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right, top perspective view of the combined phone stand and speaker in an alternate position; and,

FIG. 10 is an enlarged view of detail 10 in FIG. 1.

The dot dash broken lines encircling a portion of the combined phone stand and speaker in FIG. 1 and illustrated in the enlarged view of FIG. 10 form no part of the claimed design.
